SPRINKLER

Ivar Jepson, Oak Park, Ill., assignor to Sunbeam Corporation, Chicago, Ill., a corporation of Illinois

Application May 19, 1948, Serial No. 28,020

13 Claims. (Cl. 299—69)

1

This invention relates to sprinklers and more particularly to water sprinklers of the reaction vane type for lawns and horticultural use.

Sprinklers of the above type have not, heretofore, been altogether satisfactory. For example, certain prior sprinklers have been of the one arm single nozzle type. Due to the fact that part of the velocity head of the water being discharged from this nozzle is lost during impingement of the water on the reaction vane the distance at which such sprinklers are effective is limited. Another objection to such reaction vane type of sprinklers is that on windy days the sprinklers do not operate satisfactorily since the stream between the discharge nozzle and the vane is deflected with each gust of wind. As a result the rotation of the nozzle is erratic. Another difficulty with sprinklers of the above construction is that they have not given a uniform water distribution pattern. Thus at a distance from the sprinkler there is a heavier concentration of water than at the area around the base of the sprinkler.

Accordingly, an object of the invention is the provision in a sprinkler of the above character, of means whereby the distance at which the sprinkler is effective is increased.

Another object of the invention is the provision in a sprinkler of the above character, of means for shielding the stream being directed against the reaction vane from the effects of wind or from physical interference.

Still another object of the invention is the provision in a sprinkler of the above character, of means for deflecting and distributing a portion of water impinging on the vane to the area adjacent the base of the sprinkler, whereby a uniform water distribution pattern throughout the effective area of the sprinkler is attained.

Still another object of the invention is to provide a sprinkler of the above character which is rugged and sturdy, which is simple in construction, which has a relatively long life, and which is relatively inexpensive to manufacture.

Other objects and advantages of the invention will become apparent from the following detailed description taken in connection with the accompanying drawings, in which—

Figure 1 is a view taken substantially along the plane passing through the vertical axis of a lawn sprinkler embodying the present invention;

Fig. 2 is a top view of the sprinkler shown in Fig. 1;

Fig. 3 is an end view taken substantially along the line 3—3 of Fig. 1;

2

Figs. 4 and 5 are sectional views taken substantially along the lines 4—4 and 5—5, respectively, of Fig. 1;

Fig. 6 is a view partly in section taken substantially along the plane passing through the vertical axis of a modified form of the sprinkler embodying the present invention;

Fig. 7 is a top view of the sprinkler shown in Fig. 6;

Fig. 8 is a sectional view taken substantially along the line 8—8 of Fig. 6;

Fig. 9 is a sectional view taken substantially along the line 9—9 of Fig. 7; and

Fig. 10 is an end view taken substantially along the line 10—10 of Fig. 6.

Referring now to the drawings, the invention is shown embodied in a sprinkler adapted for sprinkling lawns, gardens, and golf courses, and also adapted generally for horticultural sprinkling. In general, the sprinkler comprises a pair of water discharging nozzles 21 and 22 mounted for rotation about a fixed axis and a reaction vane 23 normally rigid with relation to the nozzles 21 and 22 and shaped to be disposed in the discharge stream of one of the nozzles to effect rotation of the nozzles. As shown in Figure 1 the nozzles 21 and 22 are in communication with passageways 24 and 26, respectively, at opposite ends of an inclined cross arm 27 mounted for rotation about a fixed axis. The cross arm 27 is formed with a threaded opening in a boss 28 intermediate its ends and shaped to receive a threaded end portion of a vertically extending tubular spindle 29. As shown, the spindle 29 is disposed for rotation in an elongated bushing 31 supported in an upstanding sleeve member 32. The latter is screwed on a vertically extending leg 33 of an elbow 34 which has a hose connection 36 screwed into its horizontally extending leg 37. At its lower end the spindle 29 is flared outwardly to engage a shoulder 38 formed on a head 39 disposed in a chamber 41 formed in the lower end of the sleeve 32. The head 39 is of larger diameter than the opening in the bushing 31 to prevent removal of the spindle 29 from the bushing 31. To facilitate assembly and dis-assembly of the spindle, the head 39 may be formed with a slotted end portion, not shown, for the reception of a screw driver or the like. Spaced fibre discs 42 and 43 separated by a metallic disc 44 are disposed between the head 39 and an annular shoulder 46 formed at the lower end of the bushing 31 to minimize friction between the respective parts during rotation of the spindle 29. The discs also serve to prevent leakage of water along

45

50

55

the interface between the bushing 34 and the spindle 29 when the sprinkler is in operation.

The above assembly of the nozzles 21 and 22 and cross arm 27 is supported by a suitable base 47 which in this instance is of general bell shape. To this end an annular flange 48 of the bell-shaped base is clamped between a shoulder 49 on the elbow 34 and an end of the sleeve member 32. As shown, the bell-shaped base flares downwardly from its point of retention between the elbow and the sleeve to a point below the elbow and then upwardly to terminate in an outer annular rib or beaded portion 51. Spaced inwardly from the beaded portion 51, the base is formed with apertures 52 (see Fig. 2). As shown, the leg 37 of the elbow 34 projects through an opening 53 formed in the base 47.

The nozzle 21, preferably shaped to discharge what may be termed a full stream, is threaded into the upper end of the cross arm 27 and is positioned so that the stream of water is discharged unimpeded radially outwardly from the spindle 29 and at an upwardly inclined angle corresponding with the axis of the nozzle 21 and the passage 24. The nozzle 22 is positioned herein so that the stream of water discharged therefrom is directed in the same general direction as the stream of water from the nozzle 21 but in spaced relation thereto. To effect the foregoing, a U-shaped conduit 54 is mounted at the lower end of the arm 27 as seen in Figure 1. A leg 56 of the U-shaped member 54 is threaded into the end of the arm 27 in communication with the passageway 26, and an opposite leg 57 is in spaced overlying relation with the leg 56. The nozzle 22 is threaded into the end of the leg 57.

The reaction vane 23 is disposed so that the stream of water discharged from the nozzle 22 impinges directly thereagainst. The speed of rotation of the sprinkler depends on the distance between the nozzle 22 and the vane 23 together with the angular position of the reaction vane. Consequently it is to be understood that the vane may be placed at any suitable distance and angular position with respect to the nozzle 22 depending on the desired rotation of the sprinkler. For purposes of illustration, in Figure 1 the vane is disposed at a position radially beyond the nozzle 21. Herein the vane is in the form of a tab formed on the end of a tubular shield 58, the purpose of which will presently appear. The tab 23 is rigidly supported at the outer end of the shield by suitable ribs 59 and 61 integral with the end of the shield 58. The latter ribs are inclined or curved out of the plane of the vane and also serve to deflect water impinging against the vane 23 in a generally upwardly and downwardly direction to a confined pattern. As shown in Fig. 4 the vane 23 is inclined at an angle with respect to the vertical plane passing through the longitudinal axis of the tube 58. With reference to Fig. 5, it will be seen that an extreme outer end 62 of the vane 23 is also deformed in a slight curvature out of the plane of the vane 23. This deformation of the vane 23 causes a portion of the water being impinged against the vane 23 to be deflected in the form of mist falling in an area adjacent to the spindle 29. The above construction and arrangement of the vane 23 with its deformed edge portions provides a uniform water distribution throughout the effective area of the sprinkler, that is, between the axis of rotation of the spindle 29 and the extreme distance reached by the water discharged from the nozzle 21.

The speed of rotation of the nozzles 21 and 22 may be varied by changing the position of the impinging stream on the vane 23 so that more or less water may be directed against the latter. To effect this change the position of the nozzle 22 may be adjusted by rotating the U-shaped member 54 about the leg 56 which is threaded into the lower end of the arm 27. To facilitate rotating the U-shaped member 54, a suitable web 63 is provided between the legs 56 and 57.

Provision is made for shielding the stream being directed against the vane 23 so that gusts of wind or other physical means do not interfere with the efficient operation of the sprinkler. For this purpose the generally tubular member 58 is mounted to overlie the cross arm 27 and extends between the nozzle 22 and the vane 23, which as shown in this instance, is formed by the tab on the upper end of the tubular member 58. At its lower edges, side walls 60 of the member 58 are spaced apart by shoulders 64 and 66 formed at opposite ends of the cross arm 27 as shown in Figs. 1 and 3. Screws 67 and 68, respectively, threaded into the shoulders 64 and 66 rigidly secure the shield member 58 to the cross arm 27. Another factor in avoiding the effects of wind is the arrangement of the cross arm 27 and the shield member 58 substantially in dynamic balanced relation to the vertical axis mounting about which these parts rotate.

The operation of the above sprinkler may be readily understood from the foregoing but is here summarized briefly. When the sprinkler is connected to a hose, water flows through the elbow 37, the hollow spindle 29, the passageway 24, and is discharged through nozzle 21. The stream of water being discharged from nozzle 21 is unimpeded in its flow and because of the angle or elevation of the nozzle, this stream is distributed over the widest area. Simultaneously, water flows through the passageway 26 through the U-shaped member 54 and is discharged through the nozzle 22. The stream of water discharged from nozzle 22 impinges against the reaction vane 23. This impingement of the water effects rotation of the nozzles. The vane 23 is positioned so that portions of the water impinging against the vane 23 are deflected to assure a uniform water distribution pattern throughout the distance from the axis of rotation of the nozzles to the area covered by the water discharged from the nozzle 21. The speed of rotation of the nozzles may be varied by changing the position of the nozzle 22 with respect to the vane 23 so that more or less of the stream discharged therefrom impinges against the vane 23.

In Figs. 6-10 the invention is shown embodied in a sprinkler better adapted for larger areas such as on golf links and for horticultural or agricultural purposes. In this embodiment two nozzles 71 and 72, in communication with passageways 73 and 74, respectively, are mounted at opposite ends of an inclined cross arm 76 mounted for rotation about a fixed axis. The nozzle 71 is positioned to discharge radially outwardly from the fixed axis and the nozzle 72 is mounted at one end of a leg of a U-shaped member 75 in communication with the passageway 74 to reverse the direction of flow of the water in passageway 74 so that nozzle 72 discharges in the same direction as the nozzle 71. The arm 76 is formed with a boss 77 having a threaded opening for the reception of a threaded end of a tubular spindle 78. The latter is rotatably mounted by a sleeve member 79

supported at its lower end by an elbow 81 connected to a conduit 82. The spindle 78 is formed with an enlarged portion 82 adjacent to its lower end. The enlarged portion is disposed in a chamber 83 formed in the elbow 81 and is of a diameter larger than the diameter of the opening in the sleeve 79 to prevent removal of the spindle 78. Bearing members 84 and 86 are disposed between the enlarged portion 82 and an end 87 of the sleeve and a shoulder 88 formed on the elbow 81, respectively.

This nozzle assembly is mounted for ready portability. For this purpose the elbow 81 is mounted on a U-shaped strap 91 as by bolts extending through ears 92 integral with the elbow 81. At the outer end of the legs 93 and 94, respectively, the strap is formed with openings for the reception of an axle 96. Wheels 97 and 98 are secured to the axle 96 adjacent the legs 93 and 94 respectively.

As shown in Fig. 6, a reaction vane 99 is disposed between the nozzles 71 and 72. To this end the vane, disposed in a generally vertical plane, is secured as by screws 101 to an up-standing rib 102 formed on the upper end of the cross arm 76 adjacent to the nozzle 71. An extreme outer end 103 of the vane 99 is deformed or curved out of the plane of the vane as seen in Fig. 8 in a manner described for the embodiment shown in Figs. 1-5. Also, as shown in Fig. 9, upper and lower edges 104 and 106 of the vane 99 are curved out of the plane of the vane for the purpose described for the embodiment shown in Figs. 1-5. A wind shield 107 is formed by a member having a generally U-shaped cross section as seen in Fig. 10. The shield 107 is secured to the cross arm 76 as by screws 108 threaded into shoulders 109 for spacing the side walls of the shield 107. The operation of this embodiment is the same as that described for the sprinkler shown in Figs. 1-5.

While I have shown several embodiments of my invention it will be understood that I do not wish to be limited thereto since many modifications may be made and I therefore contemplate by the claims to cover such modifications as fall within the true spirit and scope of my invention.

I claim:

1. In a sprinkler, the combination of a support having a passageway for connection to a liquid supply, a spindle rotatably mounted on said support and having a passageway in communication with the passageway in the support, a first conduit extending substantially radially outwardly from the spindle and being in communication with said passageway in the spindle, a first nozzle at the end of the first conduit for directing the flow of liquid radially outwardly from the spindle, a second conduit in communication with said passageway in the spindle disposed on the opposite side of said spindle with respect to said first conduit and having an end portion shaped to reverse the direction of flow of liquid therethrough, a second nozzle at the end of said second conduit, and a reaction vane mounted on the first conduit between the first nozzle and the spindle and disposed in the path of fluid being discharged from said second nozzle to effect rotation of said nozzles.

2. In a sprinkler, the combination of a support having a passageway for connection to a liquid supply, a spindle rotatably mounted on said support and having a passageway in com-

munication with the passageway in the support, a first conduit extending substantially radially outwardly from the spindle and being in communication with said passageway in the spindle, a first nozzle at the end of the first conduit for directing the flow of liquid radially outwardly from the spindle, a second conduit in communication with said passageway in the spindle and having an end portion shaped to reverse the direction of flow of fluid, a second nozzle at the end of said second conduit, and a reaction vane, means for rigidly supporting said vane relative to said first conduit and disposed at a position beyond the first nozzle, said vane being disposed in the path of fluid discharged from said second nozzle to effect rotation of said first and second nozzles.

3. In a sprinkler, the combination of a support having a passageway for connection to a liquid supply, a spindle rotatably mounted on said support and having a passageway in communication with the passageway in the support, a first conduit extending substantially radially outwardly from the spindle and in communication with said passageway in the spindle, a first nozzle at the end of the first conduit for directing the flow of liquid radially outwardly, a second conduit in communication with said passageway in the spindle and extending radially outwardly from the spindle, a U-shaped conduit member having one leg connected to said second conduit and having its opposite leg disposed in spaced parallel relation with the first leg, a second nozzle connected to said opposite leg of the U-shaped member, a reaction vane, and means for supporting said vane rigidly with said first nozzle and disposed in the path of fluid being discharged from said second nozzle to effect rotation of said nozzles.

4. In a sprinkler, the combination of a support having a passageway for connection to a liquid supply, a spindle rotatably mounted on said support and having a passageway in communication with the passageway in the support, a first conduit extending substantially radially outwardly from the spindle and in communication with said passageway in the spindle, a first nozzle at the end of the first conduit to direct the flow of liquid radially outwardly, a second conduit in communication with said passageway in the spindle and extending radially outwardly from the spindle, a U-shaped conduit member having one leg connected to the end of said second conduit and having its opposite leg disposed in spaced parallel relation with the first leg, a second nozzle connected to said second leg portion of the U-shaped member, a reaction vane, means for supporting said vane rigidly with said first nozzle and disposed in the path of liquid being discharged from said second nozzle to effect rotation of said nozzles, said U-shaped member being angularly rotatable about one of its legs to vary the position of the second nozzle.

5. In a sprinkler, the combination of a support having a passageway for connection to a liquid supply, a spindle rotatably mounted on said support and having a passageway in communication with the passageway on the support, a first conduit extending radially outwardly from the spindle and in communication with said passageway in the spindle, a first nozzle disposed at the end of the first conduit to direct the flow of liquid radially outwardly from the spindle, a second conduit in communication with said passageway in the spindle and having an end portion turned

back on itself to reverse the direction of flow of liquid, a second nozzle at the end of said second conduit, a reaction vane, means for supporting said vane rigidly with said first conduit and disposed in the path of liquid being discharged from said second nozzle to effect rotation of said nozzles, and shielding means disposed between the reaction vane and the second nozzle, said shielding means providing a protected passageway for the stream of water being discharged from the second nozzle to said vane.

6. In a sprinkler, the combination of a stationary support defining a fixed axis, a nozzle mounted on said support for rotation about said fixed axis, conduit means defining a passageway through which liquid under pressure may be supplied to said nozzle for discharge therefrom as a liquid stream, a reaction vane, means for supporting said reaction vane in fixed relationship relative to said nozzle for rotation therewith and disposed in the stream of liquid discharged from said nozzle for causing rotation of said nozzle, said vane being disposed at a substantial distance from said nozzle several times the length of said nozzle whereby a free stream of liquid of substantial length exists between said nozzle and vane upon operation of said sprinkler, and shield means disposed between said nozzle and said vane for shielding the stream of liquid being discharged from the nozzle against the effects of wind or the like.

7. In a sprinkler, the combination of a stationary support defining a fixed axis, a first discharge nozzle mounted on said support for rotation about said fixed axis, conduit means defining a passageway through which liquid under pressure may be supplied to said first nozzle for discharge therefrom as a liquid stream in a direction radially outwardly from said fixed axis, a second discharge nozzle rotatable with said first nozzle and connected to said conduit means whereby a stream of liquid is discharged from said second nozzle, a reaction vane, means for supporting said reaction vane in fixed relationship relative to said nozzles for rotation therewith and disposed in the stream of liquid discharged from said second nozzle for causing rotation of said nozzles, said vane being disposed at a substantial distance from said second nozzle several times the length of either of said nozzles whereby a free stream of liquid of substantial length exists between said second nozzle and said vane upon operation of said sprinkler, and shield means disposed between said second nozzle and said vane for shielding the stream of liquid being discharged from the nozzle against the effects of wind or the like.

8. In a sprinkler, the combination of a stationary support defining a fixed axis, a first discharge nozzle mounted on said support for rotation about said fixed axis, conduit means defining a passageway through which liquid under pressure may be supplied to said first nozzle for discharge therefrom as a liquid stream in a direction radially outwardly from said fixed axis, a second discharge nozzle rotatable with said first nozzle and connected to said conduit means whereby a stream of liquid is discharged from said second nozzle, a reaction vane, means for supporting said reaction vane in fixed relationship relative to said nozzles for rotation therewith and disposed in the stream of liquid discharged from said second nozzle for causing rotation of said nozzles, said vane being disposed at a substantial distance from said second nozzle

5 several times the length of either of said nozzles whereby a free stream of liquid of substantial length exists between said second nozzle and said vane upon operation of said sprinkler, and an elongated U-shaped member defining a shield for shielding against the wind and other interferences the stream of liquid between said second nozzle and said vane.

9. In a sprinkler, the combination of a rotatable mounted first nozzle shaped to discharge an unimpeded liquid stream radially outwardly from a fixed axis, a reaction vane rigidly supported relative to said first nozzle and adjacent the discharge end of said first nozzle thereby 15 movable as a unit therewith, and a second nozzle shaped to discharge a liquid stream therefrom and mounted for rotation with said first nozzle about said fixed axis, said second nozzle being positioned on the opposite side of said fixed axis relative to said first nozzle and on a vertical plane common to said fixed axis and both of said nozzles, said second nozzle including means for reversing the direction of flow of liquid prior to discharge from said second nozzle to cause the flow of liquid therefrom to impinge against said vane to effect rotation of the first and second nozzles.

10. In a sprinkler, the combination of a stationary support defining a fixed axis, a first nozzle mounted on said support for rotation about said fixed axis and shaped to discharge liquid radially outwardly from said fixed axis, a reaction vane disposed above the longitudinal axis of said first nozzle, means for supporting said vane as a rigid unit with said first nozzle; a second nozzle mounted for rotation about said fixed axis and positioned on the opposite side of said fixed axis relative to said vane, said second nozzle being arranged to discharge liquid in a path of flow substantially parallel to and overlying the path of flow of the first nozzle to impinge against said vane whereby the reaction of the liquid in deflecting from said vane rotates said nozzles.

11. In a sprinkler, the combination of a stationary support defining a fixed axis, a first nozzle mounted on said support for rotation about said fixed axis shaped to discharge liquid radially outwardly from said fixed axis, a second nozzle disposed on the opposite side of said fixed axis relative to said first nozzle, means for supporting said second nozzle for rotation about said fixed axis in unison with said first nozzle, said second nozzle positioned to discharge liquid in the same direction as the first nozzle, a reaction vane, means for supporting said vane so as to be rigid with respect to said nozzles and disposed in the path of the discharged liquid of one of said nozzles to effect rotation of said nozzles.

12. In a sprinkler, the combination of a first nozzle disposed a predetermined distance from a fixed axis and mounted for rotation thereabout, said nozzle being shaped to discharge liquid radially outwardly from said axis, a second nozzle mounted a second predetermined distance from the fixed axis and rotatable in unison with the first nozzle, a reaction vane, means for supporting said vane rigidly with respect to said first nozzle and in a position at a distance beyond the first nozzle so that the longitudinal axis of said second nozzle beginning with the discharge end thereof intersects both the surface of said vane and said fixed axis and is generally parallel 70 to the longitudinal axis of said first nozzle, said

reaction vane being disposed in the discharge path of said second nozzle whereby the impingement of the fluid on the vane effects rotation of said nozzles.

13. The arrangement set forth in claim 11 in which said vane is disposed between said first nozzle and said fixed axis and in the path of liquid discharged from said second nozzle.
